UNITED STATES PATENT OFFICE.

ALBERT W. HULL, OF SCHENECTADY, NEW YORK, ASSIGNEE TO GENERAL ELECTRIC COMPANY, A CORPORATION OF NEW YORK.

METHOD OF AND MEANS FOR AMPLIFYING ELECTRICAL VARIATIONS.

1,313,187.

Specification of Letters Patent.

Patented Aug. 12, 1919.

Application filed November 8, 1915. Serial No. 60,401.

To all whom it may concern:

Be it known that I, ALBERT W. HULL, a citizen of the United States, residing at Schenectady, in the county of Schenectady, State of New York, have invented certain new and useful Improvements in Methods of and Means for Amplifying Electrical Variations, of which the following is a specification.

10 One of the objects of my present invention is to provide a means for amplifying electrical current, potential or energy variations of such magnitude that they cannot be readily measured or utilized to actuate desired recording devices.

In carrying my invention into effect I connect a negative resistance device in parallel with a positive resistance and impress the current, potential or energy variations to be amplified upon the circuit in which the two resistances are connected. The total current flowing in the circuit then will be the algebraic sum of the currents in the two resistances. If the two resistances are nearly equal to each other in value a very small change in the total current may cause a large change in the current through either one of the resistances.

In the following description and claims I will refer to the two resistances as being connected in parallel in a circuit when upon the closing of that circuit an equal potential is impressed upon both.

The novel features of my invention I have pointed out with particularity in the appended claims. The invention itself, however, both as to its construction and method of operation together with further objects and advantages, will best be understood by reference to the following description taken in connection with the accompanying drawing in which Figure 1 shows one system of connections which may be devised in carrying my invention into effect. Fig. 2 shows a modification thereof, and Fig. 3 shows the current characteristics of the system shown in Fig. 1.

In the arrangement shown in Fig. 1 a positive resistance 1 or other device having positive resistance characteristics is connected in parallel with a negative resistance device 2. A photo-electric cell 3 is connected in series with the two resistances and the portion 13 of the battery 4 between

the points 17 and 18 is included in the circuit to furnish current. It is a well known characteristic of photo-electric cells that when an electromotive force is applied to their terminals and the cathode, which consists of potassium, sodium or other metal having the property of emitting electrons under the influence of light, is subjected to the action of light, there will be a flow of negative electricity from the cathode to the anode and this current will be proportional to the intensity of the light falling upon the cathode. The current which is thus obtained, however, is too small to be measured by ordinary measuring instruments and the specific object of the arrangement here shown is to provide a means for amplifying this current to such a degree that it can readily be measured or utilized for any desired purpose.

The negative resistance which I prefer to utilize in the present case is one which is described and claimed in my prior application, Serial No. 47,938, filed August 30, 1915, and which consists of a highly evacuated envelop 5 provided with a tungsten filament 6 connected to leading-in conductors 7 for supplying current from the battery 8 for heating it to incandescence. This cathode is preferably surrounded by a cylindrical wire grid 9 which serves as an anode and which is connected to leading-in wire 10. Surrounding the cathode and anode is a third electrode consisting of a metal cylinder 11 connected to leading-in wire 12. This cylinder is preferably fairly close to the anode. The relative positions of the three electrodes may be varied in order to vary the operating characteristics of the device. The envelop 5 should preferably be exhausted to such a degree of vacuum that when potentials of the magnitude desired for the operation of the device are applied to the electrodes there will be no visible manifestations of gas ionization such as blue glow.

If a positive potential is impressed upon the anode 9 there will be a flow of electrons from cathode to anode. If the third electrode 11 is at the same potential as the cathode no electrons will be received thereby. If, however, a small positive potential is applied to the third electrode a portion of the electrons which pass through the grid anode will

strike it and it will receive a current of negative electricity. The velocity with which the electrons will strike the third electrode will depend upon the potential between it and the cathode. If this potential is increased the velocity will increase until the electrons striking the third electrode are able by their impact to liberate secondary electrons. These secondary electrons leaving the third electrode will be attracted to the more positive anode. As the potential is increased a point will finally be reached at which the number of secondary electrons leaving the third electrode is just equal to the number of primary electrons that strike it. That is, each electron that strikes liberates on an average one secondary electron. No current will then be received by the third electrode. If the potential of the third electrode is further increased the number of secondary electrons given off becomes greater than the number of primary electrons received and as a result the third electrode loses electrons, thereby supplying current to the anode instead of receiving current.

These characteristics can best be understood by reference to the curve shown at A in Fig. 3, in which the ordinates represent the electron current flowing to or away from the third electrode and the abscissæ represent the potential of the third electrode. The part O B represents the increasing electron current reaching the third electrode as the potential is increased. When the potential of the third electrode increases beyond that corresponding to the point B, the rate of increase in the emission of secondary electrons exceeds the rate of increase in the primary electrons received, and the current begins to decrease. When the potential of the third electrode reaches the point C it loses as many electrons as it receives and the current becomes zero. From C to D the number of secondary electrons given off continues to increase and the electron current from the third electrode to the anode increases. The point D is finally reached, however, at which the potential of the third electrode so closely approaches that of the anode that the number of secondary electrons lost by the third electrode begins to decrease because of the fact that the difference of potential between anode and third electrode is not great enough to attract as many electrons to the anode as before. This continues until the point E is reached where the number of secondary electrons which leave the third electrode and do not return, is equal to the number of primary electrons which strike it and the current again becomes zero. From this point the electron current received by the third electrode increases with increase in its potential as indicated by the part E F of the curve. The part B D of the current

curve throughout the greater portion of its length is approximately straight and the straight portion may be represented by the equation

$$I = I_0 - \frac{E}{R},$$

where E is the potential of the third electrode I_0 and R are constants, depending upon the characteristics of the particular device, and I is the electron current flowing to or away from the third electrode as

$$I_0 - \frac{E}{R}$$

is positive or negative. R corresponds to the resistance of an ordinary circuit except in this case it is a negative resistance. Thus it will be seen that there is a certain range through which the device may be operated in which the current received by the third electrode will vary inversely as the potential applied thereto. In the description which follows and in the claims the term "negative resistance" is used to designate a device having this characteristic.

In the system shown in Fig. 1 battery 4 furnishes a constant potential for the anode 9. The resistances and the potential applied thereto are preferably so adjusted that when the photo-electric cell 3 is not illuminated and hence there is no current flow therethrough there will be no current through either resistance. This may be accomplished by connecting the end of the resistance 1 to a point 17 in the battery 4, so chosen that the potential thereby applied to the third electrode 11 will correspond to the point C on the current curve. Since under these conditions no current will flow through the negative resistance there will not be any current through the positive resistance. The current through the positive resistance then under operating conditions may be represented by the straight line G which falls above or below the axis of ordinates, as indicated, with reversals in the potential applied thereto. The total current in the circuit or the current in the photo-electric cell will be the algebraic sum of the current through the two resistances. The algebraic sum of these two currents with varying potentials on the third electrode is indicated by the dotted line H. By making the two resistances approximately equal to each other in value so that the slope of curves A and G is approximately the same it will be seen that a very small change in the total current will cause a much greater change in the current through either of the two resistances and it will be apparent that the degree of amplification which can thus be secured will depend upon how closely the two resistances approach each other in value.

When the photo-electric cell is not influenced by any light source the portion 13 of battery 4 is open-circuited in so far as its effect on the current through either resistance is concerned. When the photo-electric cell is illuminated by any light source current starts to flow therethrough and there is, in effect, a potential applied to both the negative and positive resistances in parallel which is equal to the potential of the portion 13 of the battery 4 less the drop in potential through the photo-electric cell. Since the current through the photo-electric cell varies in proportion to the intensity of the illumination thereon this drop in potential will vary in proportion to the intensity of the illumination. The effect of the application of this potential, however, is not the same in both resistances. An inspection of the curves of Fig. 3 will show that a change in potential from that corresponding to point C will produce a current in one direction in the negative resistance and in the opposite direction in the positive resistance. Hence, it will be apparent that the result of applying the potential mentioned to the two resistances will be to produce a current which circulates between the two resistances and which does not flow through the photo-electric cell. The currents in the two resistances, however, will not be equal as the current in the resistance in which the current flows in the same direction as that in the photo-electric cell will be greater than the current in the other resistance by an amount equal to the current in the photo-electric cell. In other words the current through one of the resistances may be considered as made up of two parts; one part which flows through the photo-electric cell and one part which flows through the other resistance, while the current in the other resistance will be merely the current which circulates between the two resistances and does not pass through the photo-electric cell. It may be shown mathematically that the current through either resistance will bear substantially the same ratio to the current in the photo-electric cell that the value of the resistance bears to the difference between the two resistances.

In other words, the current in the recording instrument 14 or other desired device which may be inserted in series with the resistance 1 will bear the same ratio to the current in the photo-electric cell that the resistance 1 bears to the difference between the two resistances. This will be true irrespective of the nature of the current in the photo-electric cell, that is, whether it is a constant current or a pulsating current. The same amplifying action will also take place if a source of alternating current is substituted for the photo-electric cell 65 3. If the current is alternating the currents

in the two resistances will reverse in direction at the same time that the total current reverses in direction as can be seen from curves A, G and H.

In the above description it has been assumed that the total current in the circuit starts from zero or changes in sign. It is not essential however that this should be the case as the same principle can equally well be applied to the amplification of small changes in unidirectional currents of relatively large magnitude. If the resistance 1 were connected, for example, to the same point in the battery as the cathode 6 the current through the positive resistance 75 would be as indicated by the curve K and the total current in the circuit would follow the curve L. If then the total current in the circuit had such a value that it fell on the portion of the curve where the resistance 80 2 is negative, changes in current would be amplified in the same manner as in the case first described. By varying the point of connection of the resistance 1 to the battery it will be seen that the system can always be 85 adjusted so that the total current in the circuit will fall upon a portion of the curve where the resistance 2 is negative.

The form of my invention illustrated in Fig. 2 differs from that shown in Fig. 1 in 95 that the photo-electric cell is replaced by the secondary 15 of a transformer, the primary 16 of which may be supplied by a telephone current or any other variable current which it is desired to amplify.

In the above description and in the claims which follow, I have used such expressions as "current flow from cathode to third electrode" to designate the net electron current received by the third electrode, or the current which will flow in the external circuit between cathode and third electrode.

While I have described the preferred embodiment of my invention it will be apparent that many changes therein may be made 110 without departing from the scope of the appended claims. For example, in case it is desired to measure or utilize amplified potential variations the device for accomplishing the desired purpose is connected 115 in shunt to the resistance 1 instead of in series therewith. It will also be apparent that the device 14 indicated may assume a great variety of forms in accordance with the purpose which is to be accomplished.

What I claim as new and desire to secure by Letters Patent of the United States, is:—

1. Means for amplifying electrical variations comprising a positive resistance and a negative resistance in parallel therewith, the two resistances being approximately equal to each other in value.

2. Means for amplifying electrical variations comprising a device having positive resistance characteristics and a negative re- 130

sistance in parallel therewith, the two resistances being approximately equal to each other in value.

3. Means for amplifying electrical variations comprising a positive resistance, a negative resistance, and means for supplying the variations to be amplified to the two resistances in parallel.

4. Means for amplifying electrical variations comprising a negative resistance having a working range over which the current flow therethrough varies inversely as the potential applied thereto, a positive resistance, and means for supplying the variations which are to be amplified to the two resistances in parallel.

5. Means for amplifying electrical variations comprising a negative resistance having an electron emitting cathode, and having a working range over which the current flow varies inversely as the potential applied thereto, a positive resistance and means for supplying the electrical variations to be amplified to the two resistances in parallel.

25 6. Means for amplifying electrical variations comprising a negative resistance having an electron emitting cathode, an anode and a third electrode inclosed in a highly evacuated envelop, and having a working range over which the current flow from the cathode to the third electrode varies inversely as the potential applied thereto, a positive resistance and means for supplying

the electrical variations which are to be amplified to the two resistances in parallel. 35

7. Means for amplifying electrical variations comprising a negative resistance having an electron emitting cathode, an anode, and a third electrode near the anode and so positioned with respect to the cathode and anode that it will receive electrons from the cathode when it is more positive than the cathode, and so that secondary electrons given off from the third electrode can readily reach the anode, a positive resistance, and means for applying the electrical variations which are to be amplified to the two resistances in parallel. 40 45

8. Means for amplifying electrical variations comprising a negative resistance, a positive resistance, and means for supplying electrical variations which are to be amplified to the two resistances in parallel, the two resistances being approximately equal to each other in value. 50 55

9. The method of amplifying electrical variations which consists in supplying variations which are to be amplified to a positive resistance and a negative resistance in parallel, and thereby producing amplified electrical variations in the positive resistance. 60

In witness whereof, I have hereunto set my hand this 6th day of November 1915.

ALBERT W. HULL.
